UNITED STATES PATENT OFFICE.

JOHN H. ANDERSON, OF MOORHEAD, MINNFSOTA.

PORTABLE COPYING-PRESS.

SPECIFICATION forming part of Letters Patent No. 417,378, dated December 17, 1889.

Application filed August 19, 1889. Serial No. 321,223. (No model.)

To all whom it may concern:

Be it known that I, JOHN H. ANDERSON, of Moorhead, in the county of Clay and State of Minnesota, have invented certain new and 5 useful Improvements in Portable Copying-Presses; and I do hereby declare that the following is a full, clear, and exact description of the invention, which will enable others skilled in the art to which it appertains to 10 make and use the same, reference being had to the accompanying drawings, and to the letters of reference marked thereon, which form part of this specification.

My invention relates to certain improvements in portable copying-presses.

The object of the invention is to provide a portable copying-press exceedingly cheap, simple, and durable in construction, composed of a minimum number of strong parts, over- 20 coming certain disadvantages and defects in the presses of this kind heretofore in use, and which shall be very quick and easy in operation, wherein a uniform pressure will be applied to the letter throughout, and hence a 25 perfect, complete, and uniform copy obtained, and wherein the letter-copying paper, &c., can be easily placed upon the roller or cylinder within the pressure-sheet without catching or bending the paper or moving the same 30 out of place. These objects are accomplished by, and my invention consists in, certain novel features of construction and in combinations of parts more fully described hereinafter, and particularly pointed out in the claims.

Referring to the accompanying drawings, 35 Figure 1 is a perspective view of the press with the pressure sheet or shell upon the same, showing the screw clamping device. Fig. 2 is a perspective view showing the 40 pressure-sheet in its normal flat condition in readiness to receive the letter and copying-paper. Fig. 3 is a cross-section through the press with the pressure-sheet thereon, showing the removable bearing. Fig. 4 is a cross- 45 section of the cylinder with the present sheet thereon, showing a hollow cylinder.

In the drawings, the reference-letter *a* indicates a cylinder or roller constructed either of wood or of a hollow steel or iron tube, as 50 most desirable, and preferably of such diameter that its circumference will be greater than

the width of the paper from which duplicates are generally to be taken.

The pressure-sheet *b* in its normal condition stretches out flat, as shown in Fig. 2, and the dimensions of this sheet are such that when wrapped upon the cylinder it will be nearly if not quite as wide as the cylinder is long and of such length that its longitudinal edges will almost meet. These longitudinal edges are provided with heavy metal strengthening-strips *c c* upon the outer sides of the edges and rigidly and strongly secured thereto. At their centers these strips are provided with corresponding openings, each 60 closed on its outer side by a bridge or bar *f*. The opening in one strip has the lower end of a bearing-block *d* located therein and permanently secured or mounted on the bar *f* thereof, so that the screw-threaded opening *e* 70 of the block will be located the least distance possible above the outer side of the strip. The opening *f* in the opposite strip is adapted to receive the removable loose bearing-block *g*, which is provided with a hook on its lower 75 end to detachably engage the bar *f* of said opening *f*, in which block a smooth-faced portion of one end of the clamping shaft or bolt *h* is permanently journaled, the bolt being extended through the block and provided on 80 its outer end with an operating-crank, while the opposite portion of the bolt is threaded and passes through and works in said non-removable pivoted bearing-block *d*.

The operation of the device is as follows: 85 The clamping-bolt having been loosened so that the hook of the loose bearing-block can be removed from the opening in its edge of the pressure-sheet, said sheet is removed and allowed to assume its normal flat position. 90 The rubber pads or blotters and the dampened copying-paper and the letter are then arranged properly upon the pressure-sheet with the written face of the letter upon the copying-paper, and the pressure-sheet is then placed 95 upon the periphery of the cylinder with the copying material between them, and the edges of the said sheet are drawn toward each other until the hook or base of the movable bearing-block can be inserted in the opening of 100 the edge opposite to that upon which the screw-bearing is pivotally secured. The bolt

is then turned to wind up the screw, and the two edges are drawn toward each other and the pressure-sheet is uniformly tightened throughout upon the cylinder, whereby an even pressure is obtained throughout the entire surface of the letter. The pressure-sheet is preferably formed of leather with the metal binding-strips; or it can be formed of spring plate-steel normally tending to spread or straighten out flat when released. It should be observed that the bearings for the screw rod or bolt are nearly in the plane of the circle of the pressure-sheet, and hence the edges of the same are drawn directly toward each other and the pressure evenly distributed throughout the entire sheet. The fact that the edges of the pressure-sheet can be unjoined by unfastening one of the bolt-bearings from its edge and then the sheet can be laid out flat to receive the copying material is a great advantage and improvement, as the sheet and paper, &c., can be wrapped directly upon the cylinder without catching the edges or disarranging or bending the same, as is the case when the paper, &c., are first wrapped on the cylinder and then a cylindrical steel shell slipped on the cylinder; and, further, the copy obtained is perfect and uniform throughout, as there are no overlapping steel pressure-shells to crease and double the paper, and as the edges of the paper lie under the edges of the pressure-sheet there is no portion of the part of the paper between the edges of said sheet, and hence receiving no pressure. This device is exceedingly cheap and simple, but one pressure-sheet is required, and the screw-bolt has but one continuous thread, &c.

What I claim is—

1. The combination, with the roller or cylinder, of a straight flat pressure-sheet adapted to be wrapped upon said roller and upon which the copying material is laid, a screw-bolt to draw the edges of the sheet toward each other, and bearings for said bolt, one rigid and the other removably secured to its edge of the sheet, substantially as described. 40
2. The combination, with the roller, of the flexible pressure-sheet, a screw bearing-block permanently secured to one edge, a bearing-block provided with a hook to removably catch in the opposite edge of said sheet, and a screw-bolt passing through said blocks, substantially as described. 45
3. The combination, with the roller, of the leather or flexible pressure-sheet having the metal strips secured to its longitudinal edges, and the screw-bolt with its secured and removable bearings, whereby said edges can be separated, substantially as described. 55
4. In a portable copying-press, the combination, with a cylinder, of a normally flat flexible pressure-sheet separate from said cylinder and adapted to be wrapped upon the same so that the edges of the sheet will be located opposite, and means to draw said edges toward each other or allow the same to be separated when the sheet is to be removed, substantially as described. 65

In testimony that I claim the foregoing as my own I affix my signature in presence of two witnesses.

JOHN H. ANDERSON.
